INVENTOR

Jacob Schratwieser
BY Stephen J. Cox
ATTORNEY

UNITED STATES PATENT OFFICE.

JACOB SCHRATWIESER, OF BROOKLYN, NEW YORK.

FLOOR AND CEILING CONSTRUCTION.

SPECIFICATION forming part of Letters Patent No. 690,193, dated December 31, 1901.

Application filed July 22, 1901. Serial No. 69,244. (No model.)

To all whom it may concern:

Be it known that I, JACOB SCHRATWIESER, of the borough of Brooklyn, in the county of Kings, city and State of New York, have invented certain new and useful Improvements 5 in Floor and Ceiling Construction, of which the following is a specification.

My invention relates to intermediate construction adapted to be placed between the 10 joists or I-beams of the building and adapted to have the floors laid upon the upper part thereof and the ceilings hung therefrom; and its objects are, among others, to provide a light and durable fireproof construction of 15 this character which when completed will form practically a solid mass formed of the different parts hereinafter described securely united by cement, mortar, or other like substance and upon which the floors may be 20 readily laid and the ceilings hung.

It consists of the combination of parts and arrangement of details hereinafter described and claimed, and illustrated in the accompanying drawings, forming a part hereof.

25 In the said drawings, Figure 1 is a top view of a construction embodying my improvements with the upper flange of the I-beams cut away. Fig. 2 is a vertical section of the same on the line 2 2 of Fig. 1 with the means 30 for attaching the ceiling shown in Fig. 3 omitted. Fig. 3 is an enlarged sectional view similar to that of Fig. 2, showing the method of hanging the ceiling. Fig. 4 is a section on the line 4 4 of Fig. 3 looking in the direction 35 indicated by the arrow, and Fig. 5 is a modified construction showing the application of my improvements to a segmental arch.

Between the joists or I-beams A and resting upon the lower flanges thereof extend the 40 cross-pieces B, which are preferably made of T-iron. Between these cross-strips and resting their edges on the flanges of the T-irons and the I-beams are the blocks C, made of plaster, cement, or other suitable substance. 45 These blocks are provided with small mortises b along the edges, which rest upon the cross-pieces B, corresponding in depth to the thickness of the said strips, so that all four edges of the block will rest upon the flanges 50 of the said strips and beams. They are also provided with beveled edges having vertical grooves c therein and horizontal grooves c', running entirely around the said edges and crossing the vertical grooves. These grooves 55 or indentations may be of curved or angular

construction, as shown in Figs. 1 and 2 and Fig. 3, respectively, or they may be of any other desired shape. They are adapted to receive the cement, mortar, or other uniting substance which is poured into the spaces 60 between the blocks, and thus when the said uniting substance becomes set or hardened form a key which will unite the blocks, cross-pieces, and beams securely together. The lower surfaces of the blocks are provided 65 with indentations or scoring c³, which will assist the plaster of the ceiling in adhering thereto when an intermediate construction between the said blocks and ceiling is used.

For the purpose of hanging a finished ceiling I have provided the following construction: A strip of wood or other light material B' is placed on the under side of the cross-pieces B and secured thereto by means of the sheet-iron casing B², which embraces the 70 lower flanges of the strip B and the entire strip B². To these strips metal lath D may be nailed by driving through the metal sheeting B² into the strip B', and upon this lathing the plaster of the ceiling may be spread. 75

What I claim as new is—

1. In the construction of floors and ceilings the combination with joists or I-beams and cross-pieces, of blocks fitted into the 80 spaces between said beams and cross-pieces and beveled edges on the said blocks and vertical grooves in said beveled edges.

2. In the construction of floors and ceilings the combination with joists or I-beams and cross-pieces, of blocks intermediate the 85 said beams and cross-pieces and vertical grooves in the edges of said blocks and horizontal grooves therein.

3. In the construction of floors and ceilings the combination with joists or I-beams and cross-pieces, and strips of perforable material secured to the under side of said cross-pieces. 90

4. In the construction of floors and ceilings the combination with joists or I-beams and cross-pieces, and strips of perforable material secured to the under side of said cross-pieces by means of metallic sheeting surrounding the said strips and flanges. 95

Signed at the city of New York this 20th day of May, 1901.

JACOB SCHRATWIESER.
